UNITED STATES PATENT OFFICE.

CHRISTIAN H. FLECK, OF JACKSON, MICHIGAN, ASSIGNOR TO JACKSON CORSET COMPANY, OF JACKSON, MICHIGAN, A CORPORATION OF MICHIGAN.

CORSET BRASSIÈRE.

Application filed January 28, 1926. Serial No. 84,363.

My present invention relates to what I term a corset-brassière, and aims to provide a garment which will control the female figure of the wearer through the diaphragm region, and avoid unsightly bulges in the figure.

With these and other objects in view, the invention includes the novel features of construction and arrangement and combination 10 of parts hereinafter described and defined by the appended claims.

What I at present consider the preferred embodiment of my invention is illustrated in the accompanying drawing, in which:—

15 Figure 1 is a perspective view of the garment as in place on a wearer and partly opened.

Fig. 2 is an inside face view of the garment as seen when spread out flat.

20 Fig. 3 is a sectional detail.

Referring by reference characters to this drawing, the numeral 1 designates the body of the garment, made of customary shape with a closed back and open side front, the 25 edges of which may be provided with any desired closure or fastening means, shown for convenience as hooks and eyes, indicated at 1^a and 1^b. The garment may be formed of any suitable textile material, and the 30 back thereof provided with (or without) stiffening stays 2 (shown in dotted lines) inserted between the layers of which the garment is formed.

The sides are provided with inserts 3 of 35 elastic webbing.

4 designates a section loose or separate from the garment and adapted, when the garment is in place upon the wearer, to overlie the diaphragm region, the sides of 40 the diaphragm region being connected or anchored to the body of the garment at the point or points overlying the full portion of the buttock. Preferably the back portion of the garment is provided with flaps 5 having converging upper and lower edges, and the sides of the diaphragm section are 45 connected to the free edges of these flaps by elastic tapes 6. It will be observed that the parts are so shaped and connected that 50 when the diaphragm section overlies the diaphragm portion of the wearer, the elastic tapes or webs incline downwardly to the points where they unite with the free edges of the flaps.

Preferably one edge of the diaphragm 55 portion is permanently connected to its respective flap by the elastic webbing at that side, while the other edge is detachably connected, conveniently by having the free edge of the elastic webbing provided with fastening means such as hooks 6^a designed to engage with eyes 6^b on the edge of the coacting flap.

The diaphragm portion 4 may be provided with horizontally disposed flexible 65 stays indicated at 4^c in dotted lines.

Garment supporters may be provided as indicated at 7, and shoulder straps, as at 8.

By the use of such a control attachment, 70 particularly with the elastic webbing disposed at approximately the angle shown, I have found that there is an effective control of superfluous flesh, and unsightly bulges in the figure are prevented, thereby producing fashionable lines in both front and 75 back, while firm anchoring is secured.

The garment is also extremely comfortable to the wearer.

Preferably I use two elastic tapes 6 on 80 each side, the one overlapping the other, as indicated in Fig. 3.

Having thus described my invention, what I claim is:—

1. In a garment of the type described, a body portion, an independent inelastic member of sufficient area and positioned to cover the diaphragm portion of the body, and downwardly inclined elastic webbing connecting the edges of the diaphragm member 85 with the buttock portions of the garment, and constituting the sole connection between said member and the rest of the garment, said inelastic member being provided with spaced horizontally disposed flexible stays 90 positioned to engage the diaphragm. 95

2. In a garment of the type described, a body portion, flaps connected to the body portion at the buttock portions thereof, a diaphragm supporting member of sufficient 100 area to cover the diaphragm and provided with spaced horizontally disposed flexible stays positioned to engage the diaphragm and downwardly inclined elastic webbing connecting the edges of the diaphragm member with said flaps. 105

In testimony whereof, I affix my signature.

CHRISTIAN H. FLECK.
